(57) **CLAIM**

I claim the ornamental design for a tool interface for an accessory, as shown and described.

DESCRIPTION

FIG. 1 is a perspective view of an accessory, such as a plunge cut blade, having a tool interface.

FIG. 2 is a top view of the accessory shown in FIG. 1.

FIG. 3 is a bottom view of the accessory shown in FIG. 1.

FIG. 4 is a left side view of the accessory shown in FIG. 1.

FIG. 5 is a right side view of the accessory shown in FIG. 1.

FIG. 6 is a rear view of the accessory shown in FIG. 1.

FIG. 7 is a front view of the accessory shown in FIG. 1.

FIG. 8 is a perspective view of another accessory, such as a scraper blade, having a tool interface.

FIG. 9 is a top view of the accessory shown in FIG. 8.

FIG. 10 is a bottom view of the accessory shown in FIG. 8.

FIG. 11 is a left side view of the accessory shown in FIG. 8.

FIG. 12 is a right side view of the accessory shown in FIG. 8.

FIG. 13 is a rear view of the accessory shown in FIG. 8; and,

FIG. 14 is a front view of the accessory shown in FIG. 8.

Any broken line showing of the environment is for illustrative purposes only and forms no part of the claimed design.
